UNITED STATES PATENT OFFICE.

LEON OTTINGER, OF NEW YORK, N. Y.

HANDLE-ATTACHING MEANS FOR DOOR LATCHES.

Application filed July 16, 1926. Serial No. 122,762.

This invention relates to handle attaching means for door latches, and more particularly to means for attaching the operating handle shaft to the rollback of a latch mechanism of the type generally used upon automobile doors, and as exemplified, for instance by the disclosure contained in Patent No. 1,484,406, granted to me on February 19, 1924.

Generically considered, it is the aim and purpose of my present improvements to provide a simple and easily and quickly applicable means adapted to coact with the shaft end externally of the bore of the rollback to effect a rigid connection between the parts. However, in this broad aspect, the subject matter of this application is claimed in a second Patent No. 1,503,281, granted to me on June 29, 1924.

In the first of the issued patents above referred to, the application of the fastening or securing element whereby the operating shaft is connected with the rollback necessitates first the provision of an opening in or 25 through the rollback, and secondly, the provision of a coinciding opening in one wall of the latch case so that the fastening element can be applied after the latch parts are assembled and attached to the inner face of 30 the door. In the second of said issued patents, it is also necessary to provide the wall of the latch case with an opening for the insertion of the fastening element, since in this patented construction said element is 35 engaged with the shaft at a point beyond the outer end of the rollback.

It is the primary object and purpose of this invention to provide certain improvements in the construction disclosed in the 40 patent last referred to whereby the necessity of providing an opening in the wall of the latch case will be obviated, as well as the necessity of making any change whatever in the ordinary rollback as used in latches of this character. To this end, my present improvements are primarily characterized by the fact that the handle shaft at its end is longitudinally split for insertion through the bore of the rollback, said split end of the shaft being of such length that its extremity projects slightly beyond the inner end of the rollback. The opposed split parts of the shaft end at said projecting extremity thereof are provided with suitable means 45 with which a wedge or key element is adapted to be engaged to expansively spread the

split parts relative to each other into tight binding engagement with the walls of the rollback bore.

It is a further important item of my present improvements to provide said extremity of the split end of the shaft with suitably formed cam means to coact with one end of the rollback as the shaft is inserted in the bore thereof and spring the split parts of 60 the shaft towards each other, and said means when projected beyond the opposite side of said bore interlocking over the inner end of the rollback as the shaft parts resume their normal positions. In conjunction with this 65 feature, I provide the handle shaft at the inner end of its split portion with a suitable means to coact with the outer end of the rollback. Thus, any possibility of longitudinal shifting movement of the shaft end in either 70 direction relative to the rollback will be 75 precluded.

With the above and other objects in view, the invention consists in the improved handle attaching means for door latches, and in 80 the form, construction and relative arrangement of its several parts as will be herein-after more fully described, illustrated in the accompanying drawings and subsequently incorporated in the subjoined claims. 85

In the drawings, wherein I have illustrated several simple and practical embodiments of my present improvements, and in which similar reference characters designate corresponding parts throughout the several 90 views,

Figure 1 is a horizontal section of a portion of an automobile door illustrating my present invention in one embodiment thereof;

Fig. 2 is an enlarged detail horizontal sectional view showing the condition of the parts prior to the insertion of the locking wedge or key;

Fig. 3 is a similar view showing the locking wedge or key inserted and the shaft end expanded into the rollback bore;

Fig. 4 is a detail sectional view taken on the line 4—4 of Fig. 3;

Fig. 5 is a detail end elevation illustrating 105 the manner of applying the expanding and locking wedge;

Fig. 6 is a detail perspective view showing a slightly modified form of the stop pin for limiting the insertion of the split end of the 110 handle shaft through the rollback bore;

Fig. 7 is a detail horizontal section similar

to Fig. 3 showing stop shoulders integrally formed on the handle shaft to engage the outer end of the rollback;

Fig. 8 is a detail end elevation showing a slightly modified form of the locking wedge or key in its applied position;

Fig. 9 is a detail perspective view of the key member shown in Fig. 8;

Fig. 10 is an end view partly in section showing another modified construction together with part of a suitable tool for inserting or extracting the key member;

Fig. 11 is a detail elevation of the key member shown in Fig. 10;

Fig. 12 is a view similar to Fig. 10 showing another alternative form of the device;

Fig. 13 is a detail elevation of the key member shown in Fig. 12, and

Fig. 14 is a view similar to Fig. 10 showing still another modified form of the invention.

The latch construction which I have partially illustrated in the accompanying drawings, constitutes no essential feature of the present invention, and it will be clearly understood as this description proceeds that the subject matter of this application is capable of adaptation and use in connection with many different types of door latches now known in the art and which might be employed for many different purposes. In all cases where a quickly attachable and detachable connection between an operating shaft and a part to be actuated thereby may prove to be of material advantage, the invention to be presently described will be found desirable. However, since the invention has been used in connection with automobile door latches and found particularly serviceable and satisfactory, I have selected this application of the invention for illustrative purposes, and in the accompanying drawings have shown a portion of an automobile door 5. The inner face of this door is mortised in the usual manner to receive the latch casting 6 within which the latch bolt and the projecting and retracting mechanism therefor are mounted. The latch bolt retracting means includes the customary rollback 7 which is journalled for oscillating or rocking movement at its ends in spaced parts of the latch case 6. This rollback may be of any desired form requisite to insure its proper cooperation with a part of the latch bolt 55 whereby the bolt is retracted when said rollback is oscillated in one direction. In every case however, the rollback 7 is provided with a bore 8 coincident with its axis of oscillation, said bore being of any desired polygonal shape in cross section. Preferably, the opposite ends of the rollback 7 are flush with the outer surfaces of the inner and outer walls respectively, of the case 6.

The door structure 5 has a transversely extending handle shaft receiving opening 9

bored therethrough substantially in line with the rollback 7. In the outer end of this opening, a combined handle shaft bearing and escutcheon member 10 is secured. This member which is preferably in the form of a sheet metal bushing having an enlarged annular head at the outer face of the door within which a yieldable bushing of felt or other compressible material is contained, constitutes no essential part of the present disclosure, as it is fully shown, described and claimed in my co-pending application for patent Serial No. 696,426, filed March 3, 1924. It will therefore, suffice to state that this member affords a conformable bearing support for the handle shaft automatically accommodating itself to any discrepancies in axial alignment between the opening 9 and the rollback 7 and likewise provides a more or less ornamental escutcheon surrounding the handle shaft at the outer face of the door.

The handle shaft includes a cylindrical portion 11 extending through the member 10 and a reduced portion 12 of the same cross sectional form as the bore 8 of the rollback 7. The end of this shaft section 12 is provided with a central longitudinally extending slit or kerf 13 therein to provide the two laterally expansible and contractable portions 14. The end faces of these shaft portions 14 are preferably slightly rounded or convex as at 15 and the outer side edge of each of said portions is formed with a narrow flange or projecting lip 16, the purpose of which will hereinafter become apparent. The inner faces of the portions 14 of the shaft end at their extremities are each provided with a groove or channel 17, the said grooves being tapered or inclined inwardly from one side face of the shaft end towards each other to the opposite side face thereof as clearly shown in Fig. 5 of the drawings.

Within the slot or kerf 13 there is loosely arranged a stop pin 18 of rectangular form in cross section, the opposite ends of which are angularly extended in reverse directions as at 19 for engagement over the opposite side faces of the shaft. As shown in Fig. 6, if desired, this stop pin may be of general I-shaped form having the heads 19' on its opposite ends each extending upon opposite sides of the shank portion of the pin. However, these suggested forms are not essential and other means for this purpose might be readily devised.

It will be understood that the length of the slot 13 in the end of the shaft and the location of the channels or grooves 17 is accurately predetermined in accordance with the length of the rollback. Thus, when this shaft end is inserted into the rollback bore from the outer end thereof, the projecting flanges or lips 16 having the rounded end faces bear against the opposite side edges of the rollback bore and as pressure is applied,

a camming action takes place whereby spaced parts 14 of the shaft are slightly sprung inwardly towards each other to a sufficient extent to permit the flanges or lips 16 to enter the bore 8 and pass therethrough. When the ends of the stop pin 18 abut against the other end of the rollback 7, the flanges 16 will then be positioned beyond the inner end of the bore 8, and the spaced parts 14 of the shaft end will resume their normal positions relative to each other, the flanges or lips 16 engaging over the inner end face of the rollback at the opposite sides of the bore 8. This condition of the parts is seen in Fig. 2 of the drawings.

It is usual to supply such doors to the automobile manufacturer with the latch applied and the upholstery indicated at 20 extending over the inner side wall of the latch case so that it only remains for the manufacturer to apply the latch operating handle. The upholstery 20 at its outer vertical edge is not tightly affixed to the wall of the latch case. Therefore, after the split end of the handle shaft has been inserted through the bore of the rollback as above explained, it is then only necessary to insert the wedge shaped locking key 21 into the widely spaced ends of the opposed grooves or channels 17 in the extremity of the shaft. This key is in the form of a comparatively thin metal strip, and as will be noted from reference to Fig. 3 of the drawings, when applied, one side of said key is in close contact with the inner end face of the rollback. A suitable tool such as that indicated in dotted lines at 22 in Fig. 4 of the drawings, may be applied for forcing the wedge or key 21 into the inclined or tapering grooves 17. The opposite edges of this key cooperating with the base walls of said grooves, exert a lateral expanding force against the parts 14 of the shaft and thereby urge the same into frictional binding contact against the walls of the bore 8 in the rollback. The key 21 is of such length that when forced in its final position by the application of the pressure jaws of the tool 22, the narrow end of said metal key is distorted or swaged over on one side face of the shaft end as indicated at 23 in Fig. 5 of the drawings, thus securely locking said key in place.

From the above description, it will be seen that I have provided an expanding means for the split end of the handle shaft whereby the same may be rigidly fixed in the bore of the rollback which is applicable at the inner extremity of the shaft so that it becomes unnecessary to provide an opening in the wall of the latch case for the insertion of the fastening element or to make any change in the usual form of the rollback. At the same time, it will be observed that there is a minimum projection of the inner end of the handle shaft beyond the inner end face

of the rollback and when covered by the upholstery 20, such projection would be scarcely observable. It will be appreciated that this expanding and locking key in conjunction with the lip 16 and the pin 18, very effectually prevent lateral or axial movement of the shaft end in either direction with respect to the rollback, resulting in practically a unitary structure wherein the two parts operate as a single element and in which it is practically impossible for the shaft end to work loose in the bore of the rollback.

In Fig. 7, I have shown a construction wherein the separate stop pin 18 is dispensed with, and in lieu thereof stop shoulders indicated at 23' are formed on opposite side faces of the handle shaft. These stop shoulders abutting against the outer end of the rollback when the split end thereof is inserted through the bore 8, subserve the same purpose as the pin 18.

In both of the constructions above described, it will be understood that the shaft end may be inserted through the bore of the rollback so that when the rollback is in its normal position, the key receiving grooves 17 in the end thereof will extend horizontally so that the expanding and locking key may be inserted from the side edge of the door, in the manner indicated in Fig. 8 of the drawings.

In Figs. 8 and 9, I show an alternative form of the expanding and locking key wherein the key 21' is of the same wedge-shaped form as above referred to but is longitudinally split as at 24 from one end thereof to a point in spaced relation to its other end to provide opposed legs 25 which are resiliently yieldable in the plane of said key. The split 24 is of such form that these legs gradually taper towards the end of the key, said legs terminating in the outwardly turned locking lugs 26 which are adapted to snap over one side face of the rollback when said key is inserted through the channels or grooves 17. The opposite end of the key is provided in its opposite side edges with sockets indicated at 27 to receive the jaws 28 of the pivotally connected lever members of tool 22', whereby said wedge member may be conveniently forced under pressure to its applied position through the grooves 17 or withdrawn therefrom in the event that it should become necessary to detach the handle shaft from the rollback.

In Figs. 10 and 11, I have illustrated another alternative construction wherein the grooves or channels 17' in the opposed faces of the split end of the shaft taper towards each other from the entrance ends of said grooves to a point about midway of their length and are then outwardly curved as at 17^a and then again slightly curved inwardly as shown at 17^b to the opposite side face of

the shaft. However, it is apparent that if desired, the base walls of these grooves might extend along straight lines in outwardly divergent relation from the intermediate portions 17^a if it is desired to simplify the mechanical operations in cutting said grooves. In conjunction with this form of the grooves 17', the expanding key member 21^a is used, said member being of the longitudinally split type to provide the resiliently yieldable legs 25^a as in Fig. 8. In this form however, said spaced yieldable legs of the expanding key are curved in general conformity with the curved sections 17^a and 17^b of the groove 17'. It will therefore, be understood that as this key 21^a is forced through said grooves, as the ends of the legs 25^a approach the intermediate sections 17^a of the grooves, they will be sprung inwardly towards each other and after passing said intermediate portions of the grooves will expand outwardly to their normal positions so that when the wedge or key is finally driven home, it will be securely locked to hold the split portions of the shaft in expanded relation to the bore of the rollback. In this instance, I have shown the key member 21^a at its wider end provided with a central opening 29 to receive a pin or stud 30 in the end of a tool bar 31 whereby said key may be readily inserted into the grooves 17' or extracted from its applied position.

In the modification shown in Figs. 12 and 13, the entrance ends of the key-receiving grooves shown at 17^c extend in substantially parallel relation to each other and the remaining portions of the grooves have their base walls curved to the opposite side face of the shaft end as at 17^a. The longitudinally split expanding key is provided with the relatively wide resiliently yieldable legs 25^a, the outer side edges of which are longitudinally curved to cooperate with the curved sections 17^a of the base walls of the grooves in the shaft end. It will be understood that when this key is inserted, said outer edges of the legs 25^a engage the parallel end portions 17^c of the groove walls, and as the curved edges of said legs ride against said walls, the legs are forced inwardly towards each other until the key is inserted when they expand to their normal positions and interlock with the sections 17^a of the grooves to hold the split end of the shaft expanded against the walls of the rollback bore.

Fig. 14 shows another possible construction in which the grooves 17^e are relatively wide and do not extend entirely across the opposed faces of the shaft portions 14. The base walls of the grooves at the entrances thereof extend for a short distance in parallel relation to each other and are then curved as at 17^f, said curved sections terminating upon the inner face of the shaft

portion 14. In this case, the locking key is in the form of a metal disc 21^e, the diameter of which is greater than the distance between the base walls of the grooves 17^e at the entrances thereof. Thus as this disc is forced under pressure into said grooves the parts 14 of the shaft are expanded, said disc being finally seated against the curved wall sections 17^f whereby the disc is held or retained in its locking position to maintain the frictional pressure of the shaft end with the walls of the rollback bore.

From the foregoing description considered in connection with the accompanying drawings the construction, manner of use and various advantages of the several illustrated embodiments of my invention will be clearly understood. It will be seen that I devised very simple means whereby the shaft may be securely locked in connection with the rollback and which overcomes possible objections to the means which I have heretofore devised for this purpose as shown in the issued patents above identified. Any one of the several expanding and locking means for connecting the shaft end with the rollback can be very easily and quickly applied with or without the use of a common tool.

I have herein disclosed several different structural forms of the shaft and expanding and locking key members, but it will be understood that it is also possible to devise various other alternative forms of this feature of my present improvements, and I accordingly reserve the privilege of adopting all such legitimate changes therein as well as in the particular form or construction of the handle shaft itself, as may be fairly incorporated in the spirit and scope of the invention as claimed.

I claim:

1. In combination, an actuating member having a shaft receiving bore, and an operating shaft for said member having a longitudinally extending slot at one end thereof providing spaced portions resiliently yieldable relative to each other, and each of said shaft portions having a cam lip at its outer end to coact with an end edge of said bore as the shaft end is inserted therein to spring the shaft portions inwardly towards each other whereby said lips may pass through the bore, and said shaft portions expanding to their normal positions when the shaft end is fully inserted whereby said lips are engaged over the other end edge of said bore to prevent withdrawal of the shaft end therefrom.

2. In combination, an actuating member having a shaft receiving bore, and an operating shaft for said member having a longitudinally extending slot at one end thereof providing spaced portions resiliently yieldable relative to each other, and each of said shaft portions having a cam lip at its

outer end to coat with an end edge of said bore as the shaft end is inserted therein to spring the shaft portions inwardly towards each other whereby said lips may pass through the bore, and said shaft portions expanding to their normal positions when the shaft end is fully inserted whereby said lips are engaged over the other end edge of said bore to prevent withdrawal of the shaft end therefrom, and a locking member adapted for insertion in said slot at the projecting end of the shaft transversely thereof and coacting with the spaced shaft portions to expand the same into tight binding engagement with the walls of said bore.

3. In combination, an actuating member having a shaft receiving bore, an operating shaft for said member having a longitudinal slot in one end providing spaced portions adapted for insertion through said bore, stop means on the shaft limiting such insertion thereof to position the free ends of said spaced portions beyond one end of the bore, and a locking member adapted to be inserted between said projecting ends of the shaft portions transversely of said slot, said shaft portions and said locking member being formed and constructed to coat with each other and expand said shaft portions into tight binding engagement with the walls of said bore.

4. In combination, an actuating member having a shaft receiving bore, an operating shaft for said member having a longitudinal slot in one end providing spaced portions adapted for insertion through said bore, stop means on the shaft limiting such insertion thereof to position the free ends of said spaced portions beyond one end of the bore, and a locking member adapted to be inserted between said projecting ends of the shaft portions transversely of said slot, said shaft portions and said locking member being formed and constructed to coat with each other and expand said shaft portions into tight binding engagement with the walls of said bore, said locking member at one of its ends having a part adapted for engagement with one side face of the shaft end to retain said locking member in its applied position.

5. In combination, an actuating member having a shaft receiving bore, an operating shaft for said member having a longitudinal slot in one end providing spaced portions adapted for insertion through said bore, said shaft at one end of said slot having stop means to engage one end of said member and limit the insertion of the shaft end into the bore, the free ends of said spaced portions projecting beyond the opposite end of said member, said projecting ends of the shaft portions having transversely extending grooves in their opposed faces, and a locking key adapted for insertion in said grooves

and coacting with the walls thereof to expand said shaft portions into tight binding engagement with the walls of said bore.

6. In combination with a latch mounted upon the inner face of a door and having a rollback provided with a bore, an operating handle shaft having a slot in one end providing spaced portions adapted for insertion through said bore, and said shaft having means limiting such insertion thereof to position the free ends of said spaced portions in projecting relation to the inner end of said bore, and a member insertable between said projecting ends of the shaft portions transversely of said slot, said member and the shaft portions having coacting parts operating to expand said shaft portions into tight binding engagement with the walls of said bore.

7. In combination with a latch mounted upon the inner face of a door and having a rollback provided with a bore, an operating handle shaft having a slot in one end providing spaced portions adapted for insertion through said bore, and said shaft having means limiting such insertion thereof to position the free ends of said spaced portions in projecting relation to the inner end of said bore, said projecting ends of the shaft portions being provided with transverse grooves in their inner opposed faces, and a key member adapted for insertion through said grooves and cooperating with the walls thereof to expand the shaft portions into tight binding engagement with the walls of said bore, one end of said key member when inserted extending beyond one end of said grooves and adapted to be engaged upon one of the side faces of said shaft portions to retain the key member in its applied position.

8. In combination with a latch mounted upon the inner face of a door and having a rollback provided with a bore, an operating handle shaft having a slot in one end providing spaced portions adapted for insertion through said bore, and said shaft having means limiting such insertion thereof to position the free ends of said spaced portions in projecting relation to the inner end of said bore, said projecting ends of the shaft portions having transversely extending grooves in their opposed faces and the base walls of said grooves convergently inclined towards each other from one side of the shaft end to the other, and a wedge-shaped key member adapted for insertion through said grooves and cooperating with the base walls thereof to expand said spaced portions of the shaft into tight binding engagement with the walls of said bore.

9. In combination with a latch having a rollback provided with a bore, an operating shaft adapted for insertion in said bore and having locking member engaging means, and a locking member consisting of a flat metal

plate adapted for engagement with said means to yieldingly urge the shaft laterally against the wall of said bore and said member also cooperating with said rollback to prevent the withdrawal of the shaft end from the rollback bore.

10. In combination with a latch having a rollback provided with a bore, a shaft adapted for insertion at one of its ends through the rollback bore and having spaced parts, and means for locking the shaft end within

the rollback bore including a flat metal plate adapted to be inserted between said spaced parts of the shaft in a plane at right angles to the shaft axis and cooperating with the shaft to urge the same laterally against the wall of the rollback bore. ¹³

In testimony that I claim the foregoing as my invention, I have signed my name hereto.

LEON OTTINGER.
